(57) **CLAIM**

The ornamental design for an ashtray, as shown and described.

DESCRIPTION

FIG. 1 is a left front perspective view of an ashtray showing the new design, showing the clip in an open position.

FIG. 2 is a left front perspective view of the design shown in FIG. 1 with the clip in a closed position.

FIG. 3 is a left front perspective view of the design shown in FIG. 1 with open top.

FIG. 4 is a left front perspective view of the design shown in FIG. 2 with top removed.

FIG. 5 is a top plan view of the design shown in FIG. 1.

FIG. 6 is a bottom plan view of the design shown in FIG. 1.

FIG. 7 is a left side elevational view of the design shown in FIG. 1.

FIG. 8 is a right side elevational view of the design shown in FIG. 1.

FIG. 9 is a rear elevational view of the design shown in FIG. 1.

FIG. 10 is a front elevational view of the design shown in FIG. 1.

FIG. 11 is a right front perspective view of the design shown in FIG. 1.

FIG. 12 is a right rear perspective view of the design shown in FIG. 1; and,

FIG. 13 is a left rear perspective view of the design shown in FIG. 1.
